FIG.1

FIG.2

FIG. 3

FIG. 4

FIG. 1 is a front, top and right side perspective view of a dictating machine, showing my new design;

FIG. 2 is a left side, top and front perspective view;

FIG. 3 is a top plan view; and

FIG. 4 is a right side elevational view, the left side being substantially a mirror image thereof.

The broken line showing of tape reels is for illustrative purposes only.

The dominant features of my new design are shown in solid lines in the drawing.

I claim:

The ornamental design for a dictating machine, as shown and described.
